UNITED STATES PATENT OFFICE.

CARL EDWARD BAUER, OF HAMMOND, INDIANA, ASSIGNOR TO SIMPLEX RAILWAY APPLIANCE COMPANY, OF CHICAGO, ILLINOIS, A CORPORATION OF ILLINOIS.

REINFORCED BRAKE-BEAM.

No. 813,612.

Specification of Letters Patent.

Patented Feb. 27, 1906.

Application filed June 1, 1905. Serial No. 263,238.

To all whom it may concern:

Be it known that I, CARL EDWARD BAUER, a citizen of the United States, residing at Hammond, in the county of Lake and State 5 of Indiana, have invented certain new and useful Improvements in Reinforced Brake-Beams, of which the following is a specification.

My invention relates to beams made of 10 rolled commercial iron such as I-beams, and particularly to means for strengthening the central portion of brake beams and the like, its objects being particularly to reinforce the 15 compression and tension flanges at the part of the beam which receives the greatest bending strain, and to provide a superior form of reinforcing sheath which may be slipped upon the beam after being formed up. The invention is shown in preferred forms in the 20 accompanying drawing, in which

Figure 1 is a side elevation of a brake beam with the brake head left off, showing the reinforcement extending over the central half of the length and on both flanges and web;

25 Figure 2 is a cross section of the beam in Figure 1; and Figure 3 is a similar section of a modification omitting the web portion of the reinforcement.

In this instance I have shown an I-beam, 4, 30 having the tension flange 5 and the compression flange 6, both surrounded by sheaths formed of plate metal, to give them additional strength. The sheath or casing 8, as shown in Figure 2, envelops the flange and a 35 portion of the web, and may be shrunk on to make a tight fit, and is riveted by rivets 9 to the web of the beam 4. Each of the sheaths has one short wing lying against the flange, and one long wing 7, extending beyond the 40 middle so as to overlap the corresponding long wing of the sheath on the other side, as will be plain.

In some cases the reinforcing sheath may engage the flange alone, as shown at the 45 lower part of Figure 3, and in other cases it may be extended to engage the web and be riveted thereto as shown at 10 in the upper part of Figure 3. Where the reinforcement is mainly to stiffen the flange the sheath 11

need not be riveted. The beam as designed 50 in Figure 3 is intended also to both stiffen and add to the tensile strength of the upper flange.

By this means the brake beam may be strengthened at just the point where the 55 greatest bending moment is applied, and thus obtaining greater economy in metal, using a lighter commercial I-beam than would otherwise be necessary. Other advantages will readily occur to those familiar 60 with the use of such devices.

Having thus described my invention and illustrated its use, what I claim as new, and desire to secure by Letters Patent, is the following:

1. A flanged beam, having a reinforcing sheath of metal extending for a portion of its length and adapted to stiffen the beam at the point of greatest bending moment, such sheath engaging the flange on both surfaces. 70

2. A brake beam having plate metal sheaths closely fitting and surrounding the flanges of the beam, and riveted to the web, said sheaths extending over the central portion of the beam. 75

3. The combination with an I-beam, of a reinforcing sheath enveloping each flange and having each a narrow and a wide wing, the respective wide wings projecting over each other and both riveted to the web of the 80 beam.

4. In a brake beam a reinforcement comprising a rolled plate metal sheath extending over the central part of the beam and enveloping the flange and riveted to the web, 85 substantially as described.

5. A brake beam having plate metal sheaths closely fitting and surrounding the flanges and web of the beam, said sheaths extending over a portion of the length of the 90 beam.

In testimony whereof I have hereunder signed my name in the presence of the two subscribed witnesses.

CARL EDWARD BAUER.
